UNITED STATES PATENT OFFICE.

JOSEPH HUEBSCH, OF MILWAUKEE, WISCONSIN.

NAP-BRUSHING MACHINE.

Application filed December 31, 1923. Serial No. 683,607.

To all whom it may concern:

Be it known that I, JOSEPH HUEBSCH, a citizen of the United States, and a resident of the city of Milwaukee and State of Wisconsin, have invented certain new and useful Improvements in a Nap-Brushing Machine; and I do hereby declare that the following is a full, clear, and exact description of the same, reference being had to the accompanying drawings, and to the numerals of reference marked thereon, which form a part of this specification.

This invention relates to nap brushing machines especially adapted for brushing and straightening up the nap of blankets and the like after they have been washed.

One of the principal objects of the invention is to provide improved means for feeding a blanket through the machine.

Another object of the invention is to provide improved means for collecting the lint, etc., removed during the brushing operation.

A further object of the invention is to provide improved controlling and operating means for nap brushing machines.

Other and further important objects of this invention will be apparent from the disclosures in the drawings and accompanying specification.

The invention (in a preferred form) is illustrated in the drawings and hereinafter more fully described.

On the drawings:

Figure 1 is a front elevation of a machine embodying the present invention.

Figure 2 is a section on the line 2—2 of Figure 1.

Figure 3 is a section on the line 3—3 of Figure 1.

Figure 4 is a section on the line 4—4 of Figure 3.

Figure 5 is a detail view showing the carded surface of one of the feed rolls.

Figure 6 is a detail view showing a part of the brush.

As shown on the drawings:

The machine comprises a pair of standards 10 connected at their rear by a flanged beam 11, and adjacent the front by a beam 12.

Between the standards is arranged a feed plate 13, over which the blanket passes from the forward compartment of a receptacle 18 to a pair of feed rolls 14 and 15.

The blanket passes around the feed roll 14 downwardly and forwardly over a guide

plate 16. In its passage over the roll 14 the blanket is engaged by the rotating brush 17, to brush up and straighten its nap. The blanket then slides down into the rear compartment of the receptacle 18. By dividing the receptacle into two compartments there is no possibility of one blanket catching on another and drawing the latter with it through the machine. This receptacle is supported by hooks 19 and 20 which releasably engage pins 21 and 22 on the standards and brackets 23 secured to such standards respectively.

Over the brush 17 is arranged a hood 24 which is extended downwards at its rear to the intake of an exhaust fan 25. The guide plate 16 is also extended up and around a supporting tube 26 to form the other part of such intake. This fan is adapted to withdraw any lint or other material removed by the brush 17, and to discharge it through opening 27 into a bag or other collecting means not shown.

The machine is driven by means of a shaft 28 journaled in the standards 10 and driven from any suitable source of power (not shown). The impeller 29 of the suction fan is directly mounted on this shaft.

The shaft 28 carries a sprocket 30 for engagement with a chain 31, which passes around a sprocket 32 on the shaft 33 which carries the brush 17. On this shaft 33 is a second sprocket (not shown) for driving a shaft 34 by means of chain 35 and sprocket 36.

The lower feed roll 14 is mounted on a shaft 37 journaled in a pair of frames 38 pivotally supported by the shaft 34. This construction allows of up and down movement of the shaft 37 without interfering with the intermeshing of the gear 39 and pinion 40 by means of which the shaft 37 is driven from the shaft 34.

The upper feed roll 15 is journaled in a pair of frames 75 pivotally supported by the shaft 33 and is driven from the shaft 37 by means of gears 41 and 42. As the roll 15 is free to rise and fall with the roll 14, the gears 41 and 42 are always in mesh.

The pinion 40 is rotatably mounted upon its shaft, but is adapted to be operatively connected thereto by means of a slidably clutch member 43. This clutch member is moved into and out of engagement by a lever 44 pivotally mounted at 45 on a bracket 46 secured to the standard.

The hand lever 47 for operating the clutch

is pivotally mounted at 48 on a member 49 oscillatable about a pin 50 so that the lever can move in two planes, one longitudinal with respect to the machine, and the other transverse. The hand lever 47 is connected to the lever 44 by means of an arm 51 having a slot 52 therein. This arm extends between the forked end of the lever 44 and is connected thereto by a pin 53 passing through the slot 52. This pin and slot connection allows the lever to swing transversely with respect to the machine without moving the clutch.

The frames 38 which carry the lower feed roll 14 are as above stated, oscillatable about the shaft 34. One of these frames is connected to the member 49 by means of links 54 and 55. These links are slidably connected together, springs 56 and 57 being provided for the purpose of resiliently holding the links in a definite position with respect to each other. With this construction, movement of the hand lever 47 transversely of the machine causes the feed roll 14 to be raised and lowered.

The hand lever 47 extends through an L-shaped slot 68 in the standard 10 so that the operations of raising or lowering the feed roll 14 and operating the clutch are performed successively and cannot be performed simultaneously.

The range of upward movement of the roll 14 may be controlled by an adjustable stop member 69 arranged in the plane of movement of the hand lever 47 and pivotally mounted at 70 on the standard 10. A rod 71 extending through an aperture in the standard is pivotally connected to the upper end of the member 69. This rod is notched on its under side for engagement with the edge of the aperture through which it passes. By this means the position of the stop member may be adjusted to limit the extent of movement of the hand-lever to any desired amount.

The feed roll 14 sometimes called a pricker roll is preferably provided with an inclined wire surface, constructed, as shown in Figure 5, of a sheet of leather 58 with a series 50 of wire staples 59 passed obliquely therethrough with the ends sharpened and projecting. These ends are arranged to project in the opposite direction to the direction of movement of the feed roll so as to 55 allow the blanket as it leaves the latter to slip off these projecting ends.

As the brush is moving in the same direction as, although much faster than the blanket, the tendency of the brush 17 is to force the blanket firmly into engagement with the projections on the roll 14.

It will be observed that the blanket travels down the guide plate 16 with its unbrushed side uppermost and is deposited in that position in the receptacle 18 so that it is positioned for re-insertion in the machine for brushing its other side.

The separation of the blanket from the pricker roll 14 is ensured by a series of cords 60 which pass around grooves in the roll 14, and a pair of grooved spacing rolls 61 and 62 journaled at their ends in the standard 10.

The other feed roll 15 may conveniently be provided with a resilient surface of 75 rubber or the like.

The brush 17 may be formed as shown in Figure 6 of a strip 63 of rubber, cloth or combination of rubber and cloth with a series of bristles 64 inserted therein.

Separation of the blanket from the brush 17 is ensured by strippers 65 mounted on the guard plate 16. For positively pushing the edge of the blanket downwards between the cords 60 and the guard plate 16, a series 85 of brushes 66 are mounted on the shaft 34.

The operation is as follows:

The motor or other means for driving the shaft 28 is placed in operation with the hand lever 47 in the position shown in Figure 90 1. With the lever in this position the clutch 43 is disconnected so that the feed or pricker roll 14 is stationary. The latter is also lowered out of engagement with the brush 17.

The edge of the blanket is then passed 95 over the feed plate 13 until it is picked up by the cords 60 and carried into the nip between the feed rolls 14 and 15.

I am aware that numerous details of construction may be varied through a wide 100 range without departing from the principles of this invention, and I therefore do not purpose limiting the patent granted otherwise than necessitated by the prior art.

I claim as my invention:

1. A nap brushing machine comprising a pair of feed rolls, one of said rolls having an inclined wire surface and the other of said rolls a resilient surface, a rotating brush adapted to engage a blanket as it passes over the inclined wire surface, the projections on said inclined wire surface extending in the opposite direction to the movement of said surface.

2. A nap brushing machine comprising a pair of cooperating feed rolls, one of said rolls having an inclined wire surface, a rotating brush adapted to engage a blanket as it passes over the inclined wire surface, the projections on said inclined wire surface 110 extending in opposite directions to the movement of said surface.

3. A nap brushing machine comprising a feed roll, a rotating brush, a second feed roll 115 movable towards and away from said brush, a driving shaft, a clutch controlled connection between said shaft and said second feed roll, and a lever adapted first to operate said clutch and then to move the second feed roll 120 towards said brush.

3. A nap brushing machine comprising a feed roll, a rotating brush, a second feed roll 125 movable towards and away from said brush, a driving shaft, a clutch controlled connection between said shaft and said second feed roll, and a lever adapted first to operate said clutch and then to move the second feed roll 130 towards said brush.

4. A nap brushing machine comprising a feed roll, a rotating brush, a second feed roll movable relative to said brush, a driving shaft, a clutch controlled connection between said shaft and said second feed roll, and a lever movable in two different planes, movement in one plane operating the clutch and movement in the other plane moving the second roll relative to said brush.
- 10 5. In a nap brushing machine, a brush roll, a pricker roll parallel thereto, a plurality of guide rolls, and flexible means passing over said guide rolls and between said brush roll and pricker roll to guide a blanket and to strip the blanket from said pricker roll.
- 15 6. A nap brushing machine, comprising a feed roll having an inclined wire surface, a second pivotally mounted feed roll having a resilient surface and riding on said first feed roll, a rotating brush and means for moving said first feed roll toward and away from said brush.
7. A nap brushing machine comprising a pair of feed rolls, one of said feed rolls being pivotally mounted to ride on the other feed roll, a rotating brush, and lever controlled means for moving one of said rolls relative to said brush.
- 20 8. A nap brushing machine comprising a rotating brush on a shaft, a feed roll movable relative to said brush, and a second feed roll pivotally supported from said shaft and riding on said first feed roll.
- 25 9. A nap brushing machine comprising a rotating brush, a pair of cooperating feed rolls, one of said rolls having an inclined wire surface, the projections on said wire surface extending in opposite directions to the movement of said surface and a flexible member passing around said wire surface roll to aid in stripping the blanket from said carded surface.

In testimony whereof I have hereunto subscribed my name.

JOSEPH HUEBSCH.
